UNITED STATES PATENT OFFICE.

OLIVER JOSEPH KING, OF HAMLET OF WINTER, SASKATCHEWAN, CANADA.

RAILWAY CROSSING.

Application filed November 17, 1926. Serial No. 148,874.

This invention relates to railroad crossings in which a plurality of planks are laid longitudinally upon the ties between the rails for the purpose of providing a level crossing surface.

These planks when so positioned extend above the normal level of the roadbed and consequently are a source of constant danger to the railway and other vehicular traffic because they are apt to be struck and displaced by dragging parts on passing rolling stock. In fact many serious accidents resulting from this cause have occurred in the past with, in some instances, loss of life.

The object of the present invention is to reduce the danger of accidental displacement of these planks to a minimum by providing means which will cause any parts hanging abnormally low on passing rolling stock to ride upwardly over the crossing without disturbing it in any way, and which will at the same time serve to anchor the crossing planks to the ties.

To this end my invention consists of the combination, construction and particular arrangement of the parts hereinafter described and illustrated and pointed out in the claim.

A practical embodiment of the invention is represented in the accompanying drawings in which similar reference characters indicate the same parts in all the views.

Referring to these drawings:

Figure 1 is a plan view of a railway crossing constructed according to my invention;

Figure 2 is a sectional view taken on line 2-2 Figure 1;

Figure 3 is a detail perspective view of one of the crossing plank plates; and

Figure 4 is a transverse sectional view taken on line 4-4 Figure 3.

In the accompanying drawings the track rails are indicated at 2, the ties at 3, the crossing planks at 4, and the means for anchoring the planks and preventing their displacement at 5.

The planks are disposed longitudinally upon the ties between the rails and their top surfaces unitedly present a crossing surface that is substantially level with the heads

of the rails as indicated in Figure 2. It is obvious that they extend a sufficient distance above the normal level of the roadbed to constitute a serious obstruction to dragging

parts on passing rolling stock and that unless means be provided which will enable such parts to pass over the planks without catching on their ends serious accidents must inevitably occur.

The means which it is believed will overcome the danger consists of one or more units located at each end of the plank group and hereinafter referred to as plank plates. In the illustrated embodiment only one of these plank plates is employed at each end of the group. Each of these plates is constituted by a unitary metallic member comprising a flat horizontally disposed plank engaging portion 6, an inclined guard or deflector portion 7 of inverted channel cross-section having vertically disposed side portions 9 and 10 respectively, and a tie-engaging portion 8. In the present embodiment in which a single plate is used to cover all the plank ends each plate is made of sufficient length to extend from one rail to within close proximity of the other, and its width is such that when mounted in position its inclined portion will present a gentle incline rising from the roadbed level to the top of the crossing. The plates are located in position with their plank engaging portions 6 overlying the adjacent ends of the planks as illustrated in Figures 1 and 2 and with their tie engaging portions 8 lying flat upon adjacent ties 12, such portions 6 and 8 being respectively secured to the planks and ties by wood screws, spikes or other preferred fastening devices 13 driven through openings 14 in the plates. When in this position the inclined surface of each plate forms a continuation of the roadbed surface and dragging parts are consequently caused to ride upwardly thereon and pass the crossing without disturbing the latter.

The side portions 9 and 10 serve to reinforce the plates and at the same time prevent moving parts from catching beneath the latter.

The transverse edges of the plates should be bevelled as at 16 and 17 respectively unless the plates at these points are countersunk in the planks and ties respectively.

What I claim is as follows:

A crossing plank plate of the type described consisting of a unitary member having an inclined deflector portion of inverted

channel cross-section, the longitudinal side edges of the latter being extended downwardly to constitute closed reinforcement side portions, horizontal extensions of the 5 top and bottom transverse edges of the said deflector portion constituting plank-engaging and tie-engaging portions, said

last-mentioned portions having transversely spaced spike openings therethrough and bevelled transverse edges, substantially as 10 described.

Signed at the hamlet of Winter, Saskatchewan, this 18th day of October, 1926.

OLIVER JOSEPH KING.
